(57) **CLAIM**

The ornamental design for a two tab suture dispensing card, as shown and described.

DESCRIPTION

FIG. 1 is a perspective view of a two tab suture dispensing card showing our new design.

FIG. 2 is a top plan view thereof.

FIG. 3 is a bottom plan view thereof.

FIG. 4 is a front elevation view thereof.

FIG. 5 is a rear elevation view thereof.

FIG. 6 is a left side elevation view thereof.

FIG. 7 is a right side elevation view thereof; and,

FIG. 8 is an enlarged partial perspective view thereof.

The broken lines in the figures form no part of the claimed design.
